CLAIM

The ornamental design for a spray and pour bottle as shown and described.

DESCRIPTION

FIG. 1 is a front perspective view of an ornamental design of a spray and pour bottle according to the present invention; FIG. 2 is a front elevational view of the spray and pour bottle of FIG. 1;

FIG. 3 is a rear elevational view of the spray and pour bottle of FIG. 1;

FIG. 4 is a left side elevational view of the spray and pour bottle of FIG. 1;

FIG. 5 is a right side elevational view of the spray and pour bottle of FIG. 1;

FIG. 6 is a top plan view of the spray and pour bottle of FIG. 1; and,

FIG. 7 is a bottom plan view of the spray and pour bottle of FIG. 1.

The broken lines shown in the drawings are for the purpose of illustrating environmental structure and form no part of the claimed design.
